FIG 1

INVENTOR

HOWARD GALBRAITH
BY

Ralph Chappell
ATTORNEY

UNITED STATES PATENT OFFICE

2,425,732

BEVEL DEVICE

Howard Galbraith, Vallejo, Calif.

Application August 8, 1945, Serial No. 609,700

2 Claims. (Cl. 33—98)

(Granted under the act of March 3, 1883, as
amended April 30, 1928; 370 O. G. 757)

1

This invention relates to a bevel device and more particularly to a device for delineating material to be cut with bevelled faces.

It is the principal object of the invention to provide a bevel device in which a plurality of bevel arms, preferably four in number, are pivotally connected with extensible body members for movement in planes substantially at right angles to each other in order to define a geometrical solid having end faces oblique to the longitudinal axis in two different planes.

It is a further object of the invention to provide for carrying out the foregoing object in a facile, economical and efficient manner.

In accomplishing these and other objects of the present invention, I have provided improved details of structure, the preferred form of which is illustrated in the accompanying drawing, wherein:

The single figure is a perspective view of a bevel device embodying the features of my invention.

Referring more in detail to the drawing:

The bevel device of my invention comprises a first body member 1 and a second body member 2, the body members preferably being in the form of elongated prisms rectangular in cross section and rounded at the outer ends.

Affixed to the first body member 1 adjacent an end thereof is an extension support member 3, which preferably carries a linear scale 4. The support member 3 extends from the inner end of the body member 1 with its longitudinal axis being substantially parallel to the longitudinal axis of the body member. The second body inner member 2 has a groove or recess 5 extending from the inner end thereof, preferably in its outer face, in which the member 3 is slidably received. Preferably a graduation 6 is marked on the face of the second body member 2 adjacent the groove or recess 5. Preferably a second extension support member 7 is affixed to one of the body members 1 or 2 and slidably received in a groove in the other body member on the faces opposite the faces on which the support member 3 is affixed and slidably received. The second extension support member 7 may be similar in construction to the extension support member 3.

The first body member 1 preferably has a channel 8 cut into the rounded outer end portion opposite the end to which the extension support 3 is affixed and the second body member 2 preferably has a similar channel 9 cut into its rounded outer end portion. The respective faces of the channels 8 and 9 are substantially co-planar.

10 A first bevel arm 10 is pivoted to the first body member 1, preferably within the channel 8, on a pivot stud 11. A second bevel arm 12 is pivoted to the second body member 2, preferably within the channel 9, on a pivot stud 13. The bevel arms 10 and 12 have straight outer edges 14 and 15 respectively that are tangential to the rounded outer ends of the body members 1 and 2 respectively. Pivotal movement of the bevel arms 10 and 12 is preferably in substantially the same plane.

15 A third bevel arm 16 is pivotally connected to the first body member 1 for movement in a plane substantially at right angles to the planes of movement of the first and second bevel arms 10 and 12. A fourth bevel arm 17 is pivotally connected with the second body member 2 for movement preferably in substantially the same plane as the movement of the third bevel arm 16.

20 The third bevel arm comprises a straight edge member 18, an outer link 19, and an inner link 20. The inner link 20 is pivoted to the first body member 1 inwardly of the first bevel arm 10 on a pivot stud 21. The outer link 19 is pivoted to the inner link 20 on a pivot stud 22 and the straight edge member 18 is pivoted to the outer link 19 on a pivot stud 23. The fourth bevel arm 17, pivoted to the second body member 2, is similar in construction to the third bevel arm 16 and hence is not described in detail.

Operation

25 The bevel device of my invention has particular application in delineating wood blocks to be cut to fit as brace members between supports in which it is necessary to provide beveled end faces oblique to the longitudinal axes of the blocks in two different planes at right angles to each other in order to achieve a satisfactory fit. An example of such an application is in the cutting of rising blocks or clamp blocks which are fitted between the frames in boat construction. The surfaces of adjacent frames in a boat are ordinarily out 30 of parallel in all planes due to the peculiar curved configuration of a boat. In order to provide firm construction in a boat, it is necessary to insert rising blocks and clamp blocks between adjacent frames to brace them.

35 40 45 50 55 In using the bevel device of my invention to delineate a block to be cut to form a rising block or a clamp block, for example, the device is placed between the adjacent frames of a boat and oriented preferably as shown in the figure. The first and second body members 1 and 2 are extended

until the ends contact the surfaces of the frames. The graduation on the scale 4 opposite to the graduation 6 on the second body member 2 is noted.

The first and second bevel arms 10 and 12 are moved about the pivot studs 11 and 13 until the straight edges 14 and 15 are in contact with the adjacent surfaces of the frames. The third and fourth bevel arms 16 and 17 are moved in planes substantially at right angles to the planes of movement of the first and second bevel arms 1 and 2 until the straight edges thereof contact the surfaces of the frames. The first and second bevel arms 10 and 12 define the vertical angles between the frames and the third and fourth bevel arms 16 and 17 define the horizontal angles between the frames.

The first and second body members 1 and 2 are moved inwardly toward each other and the device removed from between the frames. The body members are moved outwardly until the graduation 6 on the second body member 2 is aligned with the graduation on the scale 4 with which it was aligned when the device was between the frames.

The device is placed over a block of wood to be used in making the rising or clamp block and adjusted so that the first and second bevel arms 10 and 12 are against a surface and the third and fourth bevel arms 16 and 17 are against a surface at right angles to the first surface. The block of wood is marked with a suitable marking tool moved along the straight edges of the bevel arms. The block may then be cut to be used as a rising or clamp block to fit between the frames between which the measurement was taken.

I have explained the manner in which the device may be used to delineate wood blocks used as rising or clamp blocks in boat construction. However, it is obvious that the device may be used in a similar manner to delineate geometric solids of any material to be cut in numerous other applications. The use in connection with boat construction is therefore to be considered only as an example of the manner in which the device may be used.

While I have shown but one embodiment of my invention, it is apparent that the device is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A bevel device comprising an elongated first body member, an elongated second body member, an elongated extension support member having a linear scale on an outer face thereof affixed to an end portion of one of said body members and extending therefrom with its longitudinal axis substantially parallel to the longitudinal axis of the body member to which it is affixed, the other of said body members having a recess slidably receiving said extension support member, a first bevel arm pivoted to said first body member adjacent the opposite end thereof, a second bevel arm pivoted to said second body member adjacent the opposite end thereof for movement in substantially the same plane as said first bevel arm, a jointed third bevel arm pivotally connected with said first body member for movement about an axis parallel to the intersection of the plane of said first and second bevel arms with a plane normal to the longitudinal axis of said body members, and a jointed fourth bevel arm pivotally connected with said second body member for movement in substantially the same plane as said third bevel arm.
2. In a bevel device, a pair of body members connected for slidable elongation movement relative to each other, a first pair of bevel arms pivotally connected with said body members for substantially co-planar movement, a second pair of bevel arms pivotally connected with said body members for substantially co-planar movement about axes parallel to the intersection of the plane of movement of said first pair of bevel arms with a plane normal to the direction of elongation movement of said body members, each of said second pair of bevel arms including an inner link pivoted adjacent one end directly to a body member, an outer link pivoted to said inner link adjacent the other end thereof, and a straight edge member pivoted to the outer link.

HOWARD GALBRAITH.
